UNITED STATES PATENT OFFICE.

HARRY SHARDLOW, OF LOS ANGELES, CALIFORNIA, ASSIGNOR TO SOLAR ILLUMINATING CO., OF CHICAGO, ILLINOIS, A CORPORATION OF ILLINOIS.

DESIGN FOR A LIGHTING FIXTURE.

60,922.

Specification for Design.

Patented Apr. 25, 1922.

Application filed August 12, 1921. Serial No. 491,870. Term of patent 3½ years.

To all whom it may concern:

Be it known that I, HARRY SHARDLOW, a citizen of the United States, residing at Los Angeles, in the county of Los Angeles and State of California, have invented a new, original, and ornamental Design for a Lighting Fixture, of which the following is a specification, reference being had to the accompanying drawing, forming a part thereof.

The figure is a side elevation of a lighting fixture, showing my new design.

I claim:

The ornamental design for a lighting fixture, as shown.

HARRY SHARDLOW.
